10 Claims. (Cl. 33—75)

ABSTRACT OF THE DISCLOSURE

A T-square having unseparably connected blade and head elements wherein the head element is provided with two recesses under the blade. The recesses extend beyond the guiding surfaces of the blade and are disposed so that the guiding surface of the blade can be recut and the cutter of the cutting machine will not contact the head.

This invention relates to drafting or geometric instruments, and more particularly to an improved T-square, and a method and apparatus for manufacturing or repairing the same. The present application is a continuation-in-part of my co-pending applications, Ser. No. 347,070 filed on Feb. 18, 1964 now abandoned, and Ser. No. 477,074 filed July 16, 1965, now abandoned for Drafting Instrument.

Great difficulties have been experienced within the last decade with T-squares, and not only little progress has been made in providing further improvements in T-squares, but T-squares made within the last decade in accordance with conventional designs proved to be greatly inferior to similar T-squares made even as far back as 25 years ago. To appreciate fully the difficulty of the problem which those skilled in the art are now facing, one has to appreciate that T-squares have been proceeding in their progress along a path similar to that of drafting triangles. This path or direction of progress is from being an instrument made of wood to an instrument made completely of transparent plastic. In the initial stage of their development drafting triangles were made of especially selected wood, such as pear wood. In the next stage, the triangle became an instrument made of wood with plastic lined guiding surfaces, and finally it became an instrument made completely of transparent plastic. At the present time both wood triangles and triangles made of wood with plastic lined edges have completely disappeared in this country, although their use is still remembered by the older draftsmen. However, wooden drafting triangles are still in use in some foreign countries, particularly Germany.

The development of T-squares, while definitely proceeding along the same lines, has been much slower, and T-squares made completely of wood, while not used in any appreciable number by professional draftsmen, are still in use, such as in schools in classes for beginners. For professional work and advance school work a T-square with plastic lined guiding surfaces is now in wide use.

However, development of a T-square made completely of plastic material has met so many difficulties and problems that there has been a general understanding in this art that difficulties of making a T-square completely out of plastic material by cutting or milling operations from cast and annealed sheets of such material as acrylic plastic are so serious that a practical T-square of such nature is still somewhere in the distant future.

It should be understood, however, that there have been attempts of making T-squares out of transparent plastic by injection molding operations. Such operations involve melting plastic material to liquid state and injecting it into metal molds under pressure, wherein it is rapidly cooled for removal from the mold. While molded plastic items of various character are in wide use, they possess various disadvantages and advantages, their particular ad-

2

vantage being found in ease and low cost of manufacturing of intricate shapes, and their main disadvantage in short life, due to breakage mainly because of brittleness of the material.

5 The shape of T-squares is not particularly intricate, and, therefore, the above advantages is of no great value. On the other hand, brittleness of the material, resulting from its rapid cooling in the molds, proved to be a very serious disadvantage. Even a small nick on the sharp edge of the squared guiding surface of a T-square is exceedingly annoying, and in professional drafting often causes a T-square to be discarded. Even in school use, presence of several such nicks may require discarding the T-square or finding a way to remove such nicks. Use of so-called extruded strips for T-square arms connected to molded heads proved to have the same disadvantage of brittleness and ease of cracking because of internal stresses caused by the rapid cooling of the plastic material in the process of extrusion. In addition, both molded and extruded T-square blades or arms have wavy surfaces distorting the image underneath and causing eye strain in use. On the other hand, wooden T-squares with plastic lined surfaces which proved to be exceedingly durable and practical during the past 30 or 40 years proved, within the last decade, to have a tendency of disintegrating rather rapidly.

20 One of the difficulties in making T-squares entirely out of plastic material was found to be in connecting the head to the blade. While small T-squares, such as 9" in size (length of the blade), could be molded as a single piece, i.e., integrally with the head, to do so with a T-square even of such size as 24" is impractical. Connection of a plastic blade to a plastic or wooden head with the aid of screws proved to be objectionable. Drilling holes through the blade for passage of the screws weakens the blade at such places and originates cracks. Therefore, breakage of the blades through screw holes proved to be very common. Nevertheless, some of such T-squares are on the market. Together with wooden T-squares and T-squares with plastic lined edges or surfaces, such T-squares also possess the advantage of a possibility of separating the blade and the arm should it be necessary to refinish the edges of the arm because of the occurrence of nicks in the sharp edges of its guiding surfaces after a certain period of use. With the use of cast and annealed 35 acrylic plastic sheets with optically flat surfaces as a material for T-square blades, and use of construction such as disclosed in my various co-pending applications and patents, origination of nicks due to internal stresses and extension of minute cracks produced by cutters has greatly decreased, and the permanent joint between the head and the blade completely eliminated loosening of such joint. Nevertheless, some serious difficulties still remain. It has been brought out that no matter how durable and otherwise advantageous such a T-square may be and no matter how valuable is the advantage of having a non-loosening and non-separating joint between the head and the blade of such a T-square from a functional viewpoint, such joint has a great disadvantage as not permitting separation of the blade from the head for refinishing the 40 guiding edge surfaces of the T-square should, for any reason whatsoever, any nicks develop on the guiding edges of such T-squares, i.e. on the sharp edges of the squared longitudinal guiding surfaces thereof.

45 Such objection is based on the fact that the guiding surfaces of a T-square with a permanently attached head cannot be refinished on a standard machine such as a shaper or a jointer because of the interference of the head. In fact, after the appearance of all solid acrylic T-squares with permanent joints, in some instances specifications of quantity purchasers of T-squares required that the blade be separable from the head for the purposes of refinishing the guiding surfaces, it being presumed that

guiding surfaces of a T-square cannot be refinished unless the head of the T-square is first separated therefrom. It is believed that such a condition virtually blocked further progress and development of T-squares made wholly of plastic materials and making further improvements in their constructions, such as elimination of screws or other types of separable joints which are not fully suited for plastic T-squares.

An additional disadvantage of T-squares having their blades made of plastic material rather than of a wooden plank with plastic lined edges is that in case of a fall, particularly on hard cement floors, the free ends of the blades break off in substantial pieces or chip very easily. While the disadvantage of chipping of the free ends of T-squares has been greatly reduced by the construction disclosed in my said co-pending application, seemingly inexplicable breakage of large pieces at the free ends of T-square blades made even of the best acrylic material, such as cast and annealed sheet, continued.

One of the objects of the present invention is to provide an improved method and apparatus whereby guiding surfaces of a T-square having unseparable joint between its head and blade can be smoothed or refinished in a simple and easy manner and without the necessity of removal of the head or its separation from the blade.

Another object of the present invention is to provide an improved apparatus of the character specified in the preceding paragraph which is in the form of an attachment useable in combination with simple standard machines such as drill presses or routers, and with the attachment itself being of such a simple character that it can be easily manufactured or made in a school shop and as a teaching project.

A further object of the present invention is to provide an improved method and apparatus for refinishing guiding surfaces of T-squares having unseparable joints between their heads and blades, with the aid of which the guiding surfaces can be refinished with removal of a minimum amount of material from such surfaces, and without cutting any amount of material from the heads.

A still further object of the present invention is to provide an improved T-square having a construction which makes use of the method and apparatus disclosed in the present application particularly advantageous and not affecting the strength or appearance of the T-square.

A still further object of the present invention is to provide an improved method and apparatus whereby T-squares, both of unitary constructions as well as those with separable heads, which are found to have their blades secured or connected to their heads with guiding surfaces thereof not in strictly perpendicular relationship to the head can be corrected, and the guiding edges of the blades recut in strict perpendicular relationship to the guiding surface of the head.

A still further object of the present invention is to provide an improved T-square having its blade made entirely of plastic material and in which breakage of relatively large pieces at the free end of the blade is greatly reduced and virtually eliminated.

A further object of the present invention is to provide a T-square of unitary construction made of a plastic material, which T-square is particularly advantageous for having its guiding surfaces refinished by the method and with the aid of the apparatus disclosed in the present application, and in which the head is not affected in its appearance or strength by a condition that would otherwise be caused when it is attempted to refinish the guiding surfaces of the blade at the place of its juncture with the head, and in which the area of the joint between the blade and the head affecting the strength of such joint is not reduced in the process of refinishing guiding edges, and the appearance of the entire T-square is not noticeably affected by the refinishing of its guiding surfaces.

A still further object of the present invention is to provide an improved T-square having an all-plastic blade

in which the weakness of the free ends of the blade noted in such T-squares is eliminated and possibility of breakage of such ends in falling on a hard floor is greatly reduced.

5 Further objects and advantages of this invention will be apparent from the following description and appended claims, reference being had to the accompanying drawings forming a part of this specification, wherein like reference characters designated corresponding parts in the several views.

10 FIG. 1 is a view showing an improved T-square of an all-plastic construction with a non-separating joint between the head and the blade, and embodying the present invention.

15 FIG. 2 is a fragmentary sectional view taken in the direction of the arrows on the section plane passed through the line 2—2 of FIG. 1.

FIG. 3 is an elevational view on a larger scale of the head of the T-square of FIG. 1.

20 FIG. 4 is an end view taken on the T-square head of FIG. 3 with the observer looking from right to left on the guiding edge of the head.

FIG. 5 is a fragmentary perspective view showing the middle portion of the T-square head of FIGS. 3 and 4.

25 FIG. 6 is a top or plane view of the improved guiding surface refinishing apparatus embodying the present invention, with the guiding surfaces of the blade of such T-square being located therein for refinishing in such a manner that the refinished surfaces are also made perpendicular with respect to the guiding surface of the T-square head.

30 FIG. 7 is a view similar in part to FIG. 6 but showing a construction of the same general nature as in FIG. 6 but having modified locating means whereby the edges are refinished parallel to their respective original surfaces and without truing such surfaces to ensure their perpendicularity with respect to the guiding surface of the head. A portion of the device is broken off to decrease the total length of the drawing.

35 FIG. 8 is an end view with the observer looking on the construction of FIG. 7 from right to left.

FIG. 9 is a right-hand end view of the construction of FIG. 6.

40 FIG. 10 is a view showing on an enlarged scale the T-square of FIG. 1, with the middle portion of the blade thereof being broken away for compactness of the drawing.

45 FIG. 11 is a view showing on an enlarged scale the portion of the T-square encircled in FIG. 10 by the circle C.

FIG. 12 is a view similar in part to FIG. 11 but showing the cutter in its terminal position in the head recess after blade-trimming operation has been completed.

50 FIG. 13 is a view similar in part to FIG. 12 but showing the refinished blade at its place of juncture with the head, with the cutter removed.

55 It is to be understood that the invention is not limited in its application to the details of construction and arrangement of parts illustrated in the accompanying drawings, since the invention is capable of other embodiments and of being practiced or carried out in various ways. Also, it is to be understood that the phraseology and terminology employed herein is for the purpose of description and not of limitation.

60 In the drawings there is shown by way of example a T-square embodying the present invention. In addition to having the functional and structural advantages disclosed in this application, the T-square disclosed herein is particularly advantageous for having its guiding surfaces refinished with the aid of the method and apparatus disclosed below. Referring particularly to FIGS. 1-5, the T-square illustrated therein comprises a head generally designated by the numeral 10 and a blade generally designated by the numeral 11 and connected to

gether at the joint area 12 in any suitable manner such, for instance, as disclosed in my Patent No. 3,103,071.

In the top portion of the head 10 at the guiding surface thereof 14 there are provided two semi-circular recesses 15 extending downwardly approximately one-quarter to one-half of the thickness of the head. The sharp top and bottom edges of the head along the straight guiding surface 14 thereof may be beveled as indicated at 16 and 17. While along the entire lower edge and portions of the upper edge outwardly of the recesses 15 such bevel may be a straight angular bevel as indicated, on the top edge between the recesses 15 the bevel is of a modified cross section. As is shown in FIG. 5, between the recesses 15 there is provided a groove 18 having cross-section in the form of a quarter circle. It may also be in the form of an angle with rounded corner. Such form increases its holding capacity for foreign matter that may tend to be retained under the blade at its place of juncture with the head, prevents tight wedging in of foreign particles between the blade and the head at said location, and adds to the advantages in manufacturing the head and particularly in producing the joint.

It is desirable to make the head somewhat wider than has been done heretofore in order to increase the length of the end of the blade connected to the head and thus to increase the area of the joint and its strength.

The free end of the blade 11 has rounded corners and is beveled not only at its end edges but also around its rounded corners to eliminate chipping, as disclosed in my said co-pending applications.

I have discovered that breakage of large pieces from the free ends of the T-square blades made of plastic material does not result from the properties of plastic materials as such, even in cases of injection molded blades in which the material is rapidly chilled in metal molds. Such breakage results from the provision of the hole in such end as has been customarily done with T-squares for the purpose of hanging T-squares on the wall. With T-squares having blades made of wood, the provision of such holes did not affect the strength of the T-square in any appreciable degree. It has been customary to produce such holes by drilling with the hole being approximately $\frac{1}{2}$ "-. $\frac{3}{4}$ " in diameter. I have found that such holes are not suitable for plastic blades and that such holes have to be either entirely eliminated or their provision has to be done in a different manner. In accordance with the invention, the diameter of the hole 19, see FIGS. 2 and 10, provided in my improved T-square is made only $\frac{1}{4}$ " or $\frac{3}{8}$ " diameter even in T-squares as large as 36".

Such hole, while unaccustomedly small (even in the smallest T-squares such as 11" holes are presently made larger), it is, nevertheless, entirely sufficient for hanging the T-square on a hook or nail. However, decreasing the diameter of the hole increases the strength of the blade in more respects than has been heretofore appreciated in the art. It can be appreciated by analogy with other situations that providing a smaller hole leaves in the free end of the blade a greater cross-sectional area in the locality of the hole and thus does not reduce the cross-sectional area and the strength of the end in the same degree as a larger hole would.

However, it has not been appreciated heretofore that a much more important result of decreasing the diameter of the hole lies in decreasing the length of its circumference, or the length of the sharp edges of the hole, which, according to my discovery, are the main cause of breakage of the ends of plastic blades. In accordance with the invention, I increased the durability and strength of the end of my improved T-square in three main respects: first, by increasing the cross-sectional area of the blade on the plane passed through the end hole, as mentioned; second, by decreasing the length of the hole edges and the probability of developing the condition explained below; and third, by removing the strained material at the sharp edges of the hole, in which edges the cracks have already

originated or are about to originate if any additional stress is imposed thereon. The walls of the hole including their portions formed by chamfering may be polished to produce shiny surfaces and blending them into the similarly shiny surfaces of the top and bottom of the blade, thus restoring the surface tension interrupted by drilling.

As shown in FIGS. 2 and 10, the sharp edges of the blade at said hole 19 both at the top and at the bottom surfaces of the blade are chamfered or rounded for approximately .030" or more as indicated at 20 in order to remove the material at said edges. I have found that in drilling holes in plastic blades, irrespective of the type of drill used, when the blade is about to break through the bottom of the hole such breakage begins with cracking of the material around the periphery of the bottom of the hole. Thereupon, actual breaking of the drill through the plastic surface takes place by breakage of the plastic and cracking thereof, with such cracking even being audible if carefully listened to. The cracks so originated, while infinitesimally small at the start are being only approximately .010"- .012" in size and even smaller continue to grow into the body of the blade as time goes on. In the case of sudden additional stress and strain imposed on the material by the impact of a fall, the material cracks at such holes through said cracks, producing the objectionable condition referred to above.

I have also found that should extreme care be exercised and only very light pressure exerted on the drill when it is about to break through the plastic material at the bottom of the hole, the resulting condition of the material may be even worse. With very slow and careful feeding of the blade, the time of drilling the last portion of the hole is greatly increased and the friction of the drill causes heating of the adjacent portion of the material and even melting of such material immediately adjacent to the rotating drill. Such heated or molten material rapidly chills when the drill is withdrawn and sets up severe internal stresses in the material at the vicinity of the hole. Such internal stresses may originate cracks either within a very short time after completion of the drilling operation or may cause their formation later when impact strain is imposed on such material. By eliminating the affected material where cracks have already originated or are about to originate, I have produced a T-square with plastic blades, the ends of which are free from internal stresses and cracks around the edges of the hole, and eliminated the condition causing the objectionable occurrences referred to above.

As shown in FIG. 10, in addition to eliminating the serious cause of breakage by the above-described construction of the hole in the free end of the T-square, I have also reduced to a minimum and virtually eliminated the breakage of the free end of the T-square blade usually in pieces or flakes at the corners and at the transverse surface forming the end surface thereof. Such breakage has been plaguing this particular trade, and virtually each and every T-square made of acrylic plastic shows un-sightly evidence of such breakage after a relatively short period of use such as 2-3 years. Such breakage was considered to be unavoidably evil and the usual solution of this difficulty was to replace the T-square, or the blade if it was removable from the head.

In accordance with the present invention, I eliminate the above difficulty in a novel manner and virtually without any additional cost by trimming the T-square in a special manner. It is important that T-square blades should be trimmed to exactly the same length. I attain this object by trimming the free end of the blade after the blade is assembled to the head. The trimming is done with the T-square located with respect to the cutter by having the guiding surface of the head bearing on the stop means set at a predetermined distance from the trimming cutter. Instead of usual straight milling cutter, I use a grooved milling cutter with a groove of curvilinear cross section, such as arcuate and the like, in order to produce convex

cross section of the transverse end surface of the cutter, as shown in FIG. 10. Thus, in accordance with the invention the trimming operation is also a forming operation.

After completing such operation, I also trim the corners formed at the intersections of the arcuately convex end surface and the squared side guiding surfaces of the blade, preferably on a 45° angle, as shown in FIG. 10, and for a distance such as approximately $\frac{3}{16}''$ — $\frac{1}{4}''$. Thus, such corners also have convex cross section. After cutting, the convex surfaces may be sanded and steel woolled, and are buffed on the polishing wheel to restore the luster and therefore the surface tension in such surfaces. I have found that the ends of the T-square blades so constructed resist breakage, even in falls on hard surfaces such as cement floors, to such an extent as to be unexpected and surprising to those skilled in the art.

It should be understood that refinishing guiding surfaces of T-square blades may be done for two purposes: first, to eliminate nicks on the sharp edges of such surfaces; and second, to produce true perpendicularity of the guiding surfaces of the blade, i.e. to make them extend in stricter perpendicularity to the guiding surface of the T-square head.

Accordingly, there are disclosed in the present application two devices to be used for the purposes of refinishing guiding surfaces of T-squares without removing their heads. In the device illustrated in FIGS. 6 and 9 the T-square is so located during the refinishing operation that the cutter will finish the surface making it perpendicular to the guiding surface of the head. On the other hand, in the device of FIGS. 7 and 8 the T-square is so located that the cutter will refinish the surface parallel to the guiding and the guided surfaces of the device and irrespective of the perpendicularity to the guiding surface of the head. The device of FIGS. 7 and 8 is simpler in its construction, more compact and can be used to advantage where the T-square blade and head are originally assembled in proper perpendicularity, and refinishing the surfaces is done primarily to eliminate nicks or to improve their straightness.

It should be understood, of course, that in the device of FIGS. 6 and 9 both purposes may be attained simultaneously. In other words, with the use of the device of FIGS. 6 and 9, while the edge surfaces are being refinished to eliminate nicks, the perpendicularity of the guiding edge surfaces of the T-square head and of the blade may also be corrected and straightness of the blade edge surfaces improved. In this connection it should be understood that with the use of the device of FIGS. 6 and 9 it is possible to attain perpendicularity of both the upper and the lower longitudinal guiding surfaces of the T-square with respect to the guiding surface of the T-square head. It is not possible to attain such perpendicularity in the conventional method of manufacturing unless the edge surfaces of the blade are made strictly parallel. Attaining such parallelism is extremely difficult and doing so while making the blade is extremely difficult and costly. Accordingly, the device of FIGS. 6 and 9 may be used not only for refinishing guiding or edge surfaces of T-squares after a period of use but in production of new T-squares. By doing so both edges of the T-square so produced could be used in making the same drawing.

Referring specifically to FIGS. 6 and 9, the device illustrated therein is adapted to be used in combination with or as an attachment to any machine which has a work table and a cutter provided adjacent said table and rotatable around an axis perpendicular to said table. It is preferable to have the table extending horizontally and the cutter arranged above the work table perpendicularly to it, i.e. rotatable around a vertical axis. It is also desirable, but not absolutely necessary, that the cutter be vertically adjustable, and particularly that it can be moved down to a certain position, locked in said position for cutting, and thereupon raised from said position to be withdrawn from the work.

It is of importance that the device disclosed herein can be used in connection with common standard machines, particularly such machines that may be found in any school shop, such as a common drill press or a router. 5 Furthermore, the device is so constructed that it can be made very easily in a school shop and also as a teaching project by making an attachment for connection to such machine with the aid of common C clamps.

In the construction illustrated in FIGS. 6 and 9, the device is illustrated as used in combination with a common 10 drill press having a column embracing cylinder 25 and a work table 26. The supporting area of the table of such drill press is entirely sufficient to support the device attached to it with the aid of common clamps 27. However, 15 it would not be sufficient by itself to support the movable part of the device. It will be understood, however, that should there be available a machine having a work table of sufficient area and a cutter 29 as specified above, the 20 stationary part of the device can be eliminated, and merely a straightedge of metal, wood, or any other suitable material be used and secured to such table with the aid of clamps or otherwise.

The stationary or supporting and guiding portion of the device of FIGS. 6 and 9 comprises an elongated plate 25 or board 30 having length approximately twice that of the longest T-square intended to be refinished, and width approximately one-and-a-half or two times that of the length of the head. This plate may be made of aluminum or other metal, plywood board or any other suitable material. Along one of the longitudinal edges or edge surfaces of the plate or board 30 there is secured to it in any suitable manner such as with the aid of screws 31, a straightedge 32 having a guiding surface designated by the numeral 33. Straightness of the guiding surface 33 is important to ensure precision of the refinishing operation.

The movable part of the device of FIGS. 6 and 9 comprises an elongated member, plate or board 35 made of high grade plywood or aluminum and having the length substantially equal to the length of the blade of the T-square to be refinished thereon. Along one of the longitudinal edge surfaces of the board 35 there is provided a straight guided surface 36 cooperating with the straight guiding surface 33. As in the case of the guiding surface 33, straightness of the guided surface 36 is also important and for the same reasons. At the ends of the board or 40 member 35 there are provided straight locating surfaces 37 and 38 extending perpendicularly to the guided surface 36. Straightness and perpendicularity of the surface 36 and of the locating surfaces 37 and 38 are important.

Fastening means adapted to fix the T-square on the 50 board 35 in its located position are exemplified by the clamps 39 provided on said board and adapted to bear on the blade of the T-square for the purpose of holding it in place. Any desired number of such clamps may be provided. While tightening such clamps on the blade may 55 be done with the aid of common nuts tightened with the aid of a wrench, I have found that provision of wing nuts, such as 40, is sufficient to ensure proper fastening of the blade.

In order to prevent sagging or bending of the blade under pressure of the cutter 29, I provide blade-supporting means. In the present embodiment such blade-supporting means are exemplified by a wooden plank or a metal strip 45 provided with a transverse slot 46 through which passes a bolt 47 having thereon a wing nut 48. By virtue of such a construction the strip 45 may move bodily transversely of the blade 11 and rotatable around the bolt 47. A groove as indicated at 49 in FIG. 9 is provided in the board 35 for accommodating the cutter 29 and thus to permit the cutter to be moved downwardly to a position 70 when its lower extremity is below the lower surface of the blade 11 to ensure refinishing of the edge through its entire thickness.

For operation, the board 35 may be either removed from the stationary structure or moved thereon toward 75 the operator for ease of loading, and the blade 11 of the

T-square placed on the board 35 in such a position that the upper guiding surface thereof slightly overhangs the supporting edge and extends over the groove 49. Thereupon, the guiding surface 14 of the T-square head is pressed against the edge 37 to locate the T-square in the proper position. Thereupon, the amount of overhang of the edge to be refinished is checked and adjusted in order to ensure the desired depth of cut. This may be done by moving the T-square up or down with the surfaces 37 and 14 remaining in contact until the proper position is determined. It may also be done by loosening one or both clamps 27, moving the plate 30 to have the guiding surface 33 come closer or further away from the cutter 29. Thereupon, the plank 45 is moved against the lower edge surface of the blade 11, permitted to adjust itself to said edge surface and tightened. The clamps 39 are then tightened against the blade 11, and the T-square is ready for refinishing.

The board 35 is then placed with its guided edge surface 36 against the guiding edge surface 33 and the free end of the blade 11 in close proximity but not yet reaching the cutter 29. The operator then takes a firm hold of the board 35 at two convenient places, such as at clamps 39 and moves the board 35 from left to right. As soon as the end of the blade 11 touches the cutter 29, the cutter begins to take a cut and continues to do so as long as the board 35 is moved. When the head 10 of the T-square reaches the stop 50 provided substantially on the line *a—a* passing through the center of the cutter, and to a position indicated in FIG. 6 in light dotted lines, it is stopped in that position. In this position of the T-square, the cutter enters into one of the recesses 15 and therefore completes refinishing of the edge surface right to the line of its juncture with the head. Because of the provision of the recess 15, no cutting of the head and altering its appearance takes place either at the bottom or at the sides of the recess 15, see FIGS. 8, 12 and 13. When the board 35 is thus brought to a stop, the cutter is raised or the board 35 is manipulated to withdraw it away from the cutter without raising the same. Thereupon, the wing nuts 40 are loosened, and the T-square is removed. The cutter 29 should have its diameter smaller than that of the recess 15 in order to ensure sufficient clearance. I prefer to make recesses 15 to have diameter of $\frac{3}{8}$ " and $\frac{1}{8}$ " deep, and use a cutter, such as common router bit, of $\frac{1}{4}$ " diameter. With such relationship, generally illustrated in FIG. 12, it is possible to refinish the blade edge surfaces at least three times without cutting the walls of the recesses 15 and thus affecting their appearance, and at the same time to permit rapid production. However, in school shops use of $\frac{1}{8}$ " router bit allowing for larger clearance within the recesses 15, a condition desirable for an apprentice, may be more advantageous.

For refinishing the lower edge surface of the T-square blade, the T-square is turned around and is fixed on the board 35 with the guiding edge surface 14 of the T-square head in contact with the straight locating edge surface 38, i.e. in the position indicated in FIG. 6 in heavy dotted lines. Tightening of the clamps 39 and of the supporting strip 45 is made similar to that described above. The board 35 is then placed in position with the edge surface 14 of the T-square in contact with the stop 50 and the cutter 29 is lowered into the recess 15, or the board 30 is suitably manipulated to bring the cutter 29 into the recess 15. Thereupon, the board 30 is moved from left to right with the cutter performing its edge finishing operation until the T-square comes into the position to have its head in the position indicated with dash and dot line in FIG. 6, in which position of the end the free end of the blade begins to move away from the cutter 29, i.e. the edge surface of the T-square being refinished through its entire length.

It will be noted that in loading the T-square for the second part of the operation described above, i.e. refinishing the lower guiding edge surface of the blade, the sup-

porting strip 45 may be left in its tightened position when unloading the T-square after the first operation. However, inasmuch as the width of the blade will then be reduced by the amount of the cut on the upper edge of the blade, a spacer, such as a piece of wire of the thickness equal to the depth of the cut may be placed between the blade 11 and the strip 45.

It should be noted that the above specified direction of movements of the board 35 with the T-square fixed thereto with respect to the cutter 29 are selected for direction of rotation of the cutter as indicated on the drawing, in order that in cutting the cutter 29 would tend to press the work and, therefore, the board 35 against the guiding edge surface 33. Should rotation of the cutter be in the opposite direction, the direction of the movements of the board 35 would have to be correspondingly changed.

The device illustrated in FIGS. 7 and 8 is intended for refinishing the guiding edge surfaces of the T-square blade without reference to their perpendicularity to the guiding edge surface of the head. This device is smaller for the same size T-squares to be refinished, is lighter, more compact and is easier to use. It is advantageous in cases where the head and the blade are originally assembled in proper perpendicular relationship of their guiding edge surfaces and, therefore, if refinishing of the guiding surfaces of the blade is done parallel to their original guiding surfaces, such perpendicularity is preserved.

Referring specifically to FIGS. 7 and 8, the stationary portion of the device comprises a supporting board 60 and a straightedge 61 having guiding edges, i.e. squared guiding surfaces, 63 provided thereon. It will be noted that for reasons which will become clear from further explanation, the construction of the stationary portion of this device is substantially the same as that of the stationary portion of the construction of FIGS. 6 and 9 except that the board 60 is somewhat narrower than the board 30 of the device of FIGS. 6 and 9.

The movable portion of the device of FIGS. 7 and 8 comprises a plate or board 65 having provided thereon a guided edge surface 66 cooperating with the guiding edge surface 63. A locating strip 67 having a straight locating edge surface 68 is permanently secured to the board 65 in such a manner that when one edge surface of the blade of the T-square is placed tight against said edge surface 68 the opposite edge of the blade, that is, the blade to be refinished, is exactly parallel to the guided edge surface 66 of the board 65.

It should be noted in this connection that in this particular construction the end edge surfaces 69 of the movable board 65 do not serve as locating edges and may merely serve as stops for the T-square head in placing it on the board 65. In other words, the guiding edge surface of the T-square should not be pressed against the end edge surface 69 of the board 60 but should merely touch it at some point or be adjacent to it without actually contacting said edge surface 69. Location of the locating strip 67 on the board 65 is also so selected that when a blade 11 of a T-square if placed against the locating edge surface 68, the edge surface of the blade to be refinished will slightly overhang the guided edge surface 66 as illustrated, and, therefore, the cutter 29 clears said edge surface 66. A plurality of clamps 70 is provided on the board 65 to hold the blade 11 in its located position on the board 65 during the refinishing operation. Tightening of the clamps 70 is done with the aid of wing nuts 71.

It shall be understood that with T-squares having blades with edge surfaces on both sides of the blade being parallel to each other, the locating edge surface 68 of the strip 67 is disposed parallel to the guided edge surface 66. However, should T-squares having tapering blades be intended to be refinished on a device of this nature, the locating strip 67 is set to have the locating edge surface 68 make at the same angle with the guided edge surface 66 as the lower edge surface of the blade makes with the edge surface on the other side of the blade.

I have found that the devices disclosed above may be made of wood with their plates or boards being made of plywood, and straight-edges made of hard wood, such as oak, and made straight on a common woodworking machine such as a jointer. However, should particularly high precision of operation be required, metal straight-edges may be used for edges 32 and 61. Also, metal straightedges can be secured to movable boards 35 and 65 to provide guided edge surfaces 36 and 66 that are true and wear resistant.

It will be understood that the above disclosed method and apparatus are applicable with equal success for refinishing guiding surfaces of blades of T-squares other than those made entirely of plastic material as well as those having separable joints between the blade and the head. For instance, the method and apparatus disclosed herein can be used successfully and to good advantage on T-squares made entirely of wood and as well as on those having wooden blades with plastic lined edges. Even if the heads of such T-squares are separable, the use of the above disclosed method and apparatus may be advantageous as giving additional advantages such as simultaneous correction of any lack of perpendicularity.

Also, the provision of recesses such as 15 on the T-square head is not indispensable for using my method and apparatus thereon, since, in the process of refinishing, the cutter will form such recesses. The advantage of providing such recesses in advance is that such recesses may be polished and thus give the T-square head a definite and pleasing appearance which is not altered by the refinishing cutter.

FIG. 13 illustrates the appearance of the place of juncture of the head 10 with the blade 11 after the guiding edge surfaces of the blade have been refinished. It will be noted from an examination of said figure that by removing the portion 11_r throughout the entire guiding or working portion of the guiding edge surface, a rounded step 11_s having radius equal to that of the cutter 29 is formed. Said step 11_s is disposed wholly within the recess 15 and has appearance blending with that at the recess as an original design. Repeated refinishing of the edges 11 do not affect this condition, but on the contrary may improve it further. Since the center of the cutter 29 in its terminal position in the recess 15 lies within said recess, the refinished guiding edge surface is straight up to and sufficiently far beyond the guiding edge surface 14 of the head ensuring straightness of the lines drawn from the very edge surface 14.

Precision of the devices described above may be ensured with respect to the straightness of the refinished edge surfaces by lining the edges of the boards or plates thereof with steel straightedges secured thereto. To ensure perpendicularity of the blade edge surfaces with respect to the guiding edge surface of the head, the end edge surfaces 37 of the board may be also lined with a shorter straightedge which is made adjustable as to its perpendicularity with respect to the edge surface 36, such as with the use of a slot-and-screw mechanism. Such an expedient permits checking perpendicularity of the edge surfaces 36 and 37 before starting operation, and enables the operator to correct any misalignment which might have occurred.

It will be understood that the term "surface bond" and "bounding the surfaces of the head and the blade" refers to constructions in which such surfaces are secured together by the use of cements, adhesives, or by the use of solvents affecting the materials of the head and the blade. In FIGS. 10-13 location of such surfaces is designated by dotting the same.

It will be also understood that the term "guiding edge surface of the head" as well as the term "guiding edge surfaces of the blade" and the term "guiding edge of the straightedge" are used in the common manner of the art and designate, in effect, walls, or squared guiding surfaces, with each of said walls or squared guiding surfaces having a sharp top edge and a sharp bottom edge defining

or forming the boundaries of said wall surfaces. The term "elongated articulated recess" is used to designate an elongated recess having different cross-sections along the various separate portions of its length. By "cross-section" of a recess is meant the cross-section of the removed portion of the material.

In accordance with the invention, the results attainable by the construction of the head as illustrated in FIGS. 3-5 may be attained and in some instances enhanced further by cutting, against a suitable template, and in a single operation the reliefs or bevels 17 and 18 as well as both recesses 15. In such a case such bevels or reliefs, as well as the recesses will be of the same depth. Also, in the use of this method I prefer to have the recesses such as 15 to be of an elongated or rectangular form with well rounded corners. By such an expedient, I reduced the number of cutting operations from five to only one, which presents an important manufacturing advantage.

It should be understood that one of the most important advantages of the method and construction of the T-square produced thereby is the fact that elimination of concentration of localized stresses in the blade at the place of juncture with the head is attained without undercutting and thus weakening the blade by the recesses disposed at the place of the highest bending moment, and without having such recesses materially reduced or completely eliminated together with their stress-reducing advantage by recutting the side guiding surfaces of the blade. Both of such disadvantages decreasing the effectiveness of the solutions disclosed in my Patent No. 3,103,071 have thus been eliminated.

By virtue of the above disclosed construction and method, the objects of the present invention listed above and numerous additional advantages are attained.

I claim:

1. A method of making a T-square, for such T-square to have a head with a squared guiding surface and a blade having squared side guiding surfaces and one end unseparably connected to the upper surface of the head for the life of the T-square and the other end free, and to provide for repeated recutting during the life of the T-square of the side guiding surfaces of said blade without decreasing their original effective guiding length or removal of the blade from the head to eliminate interference thereof with such recutting, said method comprising the step of providing the head, prior to its connection to the blade with two recesses, each of said recesses extending into said head from the upper and guiding surfaces thereof and having substantially uniform depths to provide flat bottoms and disposed substantially at the places of intersection of the guiding surfaces of the blade with the guiding surface of the head, a substantial part of each recess underlying the blade and a substantial part of each recess being exposed beyond the corresponding guiding surface of the blade, said recess having such configuration and size as to receive therein a side milling cutter in a position normal to the plane of the blade in recutting of the respective guiding surface to its full original length but without touching any portion of the head.

2. The method defined in claim 1 with said recesses having substantially semi-circular configuration.

3. The method defined in claim 1 with recutting of the T-square being done by a side milling cutter rotating around an axis normal to the plane of the blade of the T-square and movable bodily along a straight-line path perpendicular to the guiding surface of the head between a respective recess and the end of the blade.

4. The method defined in claim 1 and including additional steps of transversely cutting the free end of the T-square blade after the same is permanently connected to the head with a curvilinearly grooved cutter to have the blade brought to precise predetermined length and in the same operation to make the transverse end surface of the blade convex, and thereupon cutting of the corners formed at the intersections of said transverse convex surface with the squared side guiding surfaces also with a

grooved cutter movable at a predetermined angle to the squared side guiding surfaces to produce straight corner surfaces of convex cross section.

5. The method defined in claim 1 with recutting of the T-square being done in a device comprising a machine having a work table, a vertically disposed side cutter provided above said table, a guiding straight surface provided on said table, a plate having a straight guided surface adapted to cooperate with said guiding surface as said plate is moved along said guiding surface, locating means on said plate to align the blade of a T-square to have its surfaces to be smoothed parallel to said guided surface, and fastening means to fix the blade of the T-square in its located position on said plate, means to adjust said guiding surface with respect to the cutters to determine the depth of the smoothing cut, stop means limiting movement of the T-square head toward the cutter substantially to a position where refinishing of the guiding surface is completed throughout its entire length.

6. The method defined in claim 5, with recutting of the squared side guiding surfaces being done in a device made in the form of an attachment to a machine having a flat horizontal work table and a vertically disposed side milling cutter provided above said table.

7. A T-square having a head with a squared guiding surface and a blade having squared side guiding surfaces, the upper surface of said head and said blade being permanently and unseparably connected together for the life of the T-square, the side guiding surfaces of said blade having continuous straight-line edges at the bottom thereof, two recesses extending into said head from the upper and guiding surfaces thereof and having substantially uniform depth and flat bottoms provided on the head, at the place of intersection of the guiding surface of the head with the guiding surfaces of the blade, a substantial part of each recess underlying said blade and a substantial part of each recess being exposed beyond the corresponding

guiding surface of said blade, said recess having such configuration and size as to receive therein a side milling cutter of at least $\frac{1}{16}$ " dia. in recutting the respective side guiding surfaces to their full original length without touching any portion of the head, and thus to provide for repeat recutting the side guiding surfaces without decreasing the original effective length thereof, without forming a step within such length, and without separating the head from the blade.

10 8. The T-square defined in claim 7 and including reliefs between the two recesses as well as between the respective recesses and the ends of the T-square head, both of said recesses and said reliefs having uniform depth in order to be all cut in a single operation.

15 9. The T-square defined in claim 7, the free end of the blade having convex cross section in its transverse end surface, with the corners formed at the intersections of said transverse end surface with the squared side guiding surfaces being removed to form corner surfaces of substantially similar convex cross sections.

20 10. The T-square defined in claim 9, with the convex surfaces of the blade being polished and buffed to restore the surface tension therein.
